(57) **CLAIM**

The ornamental design for a strip light, as shown and
described.

DESCRIPTION

FIG. 1 is a front perspective view of the strip light according
to our design;

FIG. 2 is a right side view of our design which is the mirror
image of the left side view of our design;

FIG. 3 is a top view of our design which is a mirror image
of the right side view;

FIG. 4 is a front view of our design;

FIG. 5 is a back view of our design; and,

FIG. 6 is a bottom view of our design.

The broken lines shown on the drawings are for illustrative
purposes only and form no part of the claimed design.
